UNITED STATES PATENT OFFICE

ALTON J. WELLS, OF BELL, CALIFORNIA

TOOL BOX

Application filed July 17, 1928. Serial No. 293,403.

This invention is a container for various articles and is particularly applicable for use as a tool box, a primary object of the invention being to provide a readily transportable container adapted for reception of various tools and the like in superimposed trays or compartments which may be conveniently withdrawn to permit access to the respective trays and to the body of the container.

10 It is a further object of the invention to arrange the superimposed trays for positive support with relation to the box when either withdrawn or nested in the container, and to also adapt the trays for withdrawal in opposite directions so that a pair of the trays may uncover one another and also expose the body of the box for simultaneous access thereto.

15 It is a still further object of the invention to provide an extremely practical but simple and economical supporting means for the trays, by preferably forming the supporting means as well as the main box and tray structures of suitable stamped metal having the necessary lugs formed integral with the supporting plates for cooperation with the sliding trays to support the same in either withdrawn or nested position.

20 Further objects of the invention will be readily understood from the following description of the accompanying drawings, in which:

25 Fig. 1 is a plan view of the invention showing the superimposed trays in their extended position.

30 Fig. 2 is a similar side elevation, partly broken away.

35 Fig. 3 is a fragmentary front elevation, partly broken away and showing the trays nested in the box.

40 Fig. 4 is a detail longitudinal section on the line 4—4 of Fig. 1.

45 Fig. 5 is a detail transverse section on the line 5—5 of Fig. 2.

The invention is illustrated as embodied in a container of a type adapted to form a readily transportable box for tools or the like; and is preferably of stamped sheet metal instanced as forming an open-top receptacle 1 having a cover including a top 2 and depend-

ing side walls 3, with the cover hinged to the open-top receptacle as shown at 4 so that when the cover is closed it engages the upper edge of the receptacle 1 and forms an enclosed space in the container of appreciable vertical height. The cover may be suitably locked in its closed position, as shown for example at 5, and the top 2 may be provided with a suitable handle 6 for carrying the closed container.

55 A plurality of trays 10 are supported in the upper enclosed portion of the container formed by the cover, and are adapted for sliding withdrawal when the cover is swung back to its open position in order to permit 60 convenient access to the trays and to the space within the receptacle 1. The trays are shown as supported between side plates 11 which project upwardly above the sides of receptacle 65 1 into the space defined by the closed cover, and the trays are adapted for opposite sliding withdrawal while maintaining their support between plates 11, so that by employing a pair of trays and oppositely withdrawing them, both of the trays as well as receptacle 70 75 1 will be exposed for access thereto as shown in Figs. 1 and 2. When the container is closed, the trays 10 nest one above another between the side plates 11 so that the closed cover will overlie the same as shown in Fig. 3. 80

85 The sliding mounting for each of the trays provides an adequate support for the tray when in either its retracted or extended position, and for this purpose the tray, which is preferably of stamped sheet metal, may be formed at its sides with rolled guideways 12 terminating short of the front and rear edges of the tray and adapted for sliding reception of supporting tubes 13. These tubes are in turn slidably mounted on supporting rods 14 which extend along the side plates 11, so that the trays may be retracted and extended by relative telescoping and extension of rods 14, tubes 13 and guideways 12. The relative extension and telescoping 90 of these parts may be limited by pin and slot connections, shown as pins 15 projecting from rods 14 at their inner ends and received in slots 16 extending along the tubes 13 at their outer end portions, and lugs 17 95 100

preferably integrally stamped from the outer ends of tubes 13 and received in slots 18 extending along the outer end portions of guideways 12. The slots 16-18 terminate short of the ends of tubes 13 and guideways 12 so as to form abutment means for pins 15 and lugs 17, and the parts are so arranged as to limit the extension of the tray at a point where it will just substantially clear receptacle 1, with sufficient lengths of tubes 13 still engaging rods 14 to afford adequate supports for the tubes, and preferably approximately one-half the lengths of guideways 12 engaged by the tubes 13 to adequately support the tray as shown in Figs. 1 and 2. The pin and slot connections also limit telescoping of the parts at a point substantially completely nesting tubes 13 on rods 14 with the guideways 12 in turn nested on the tubes medially of their length so as to position the tray entirely within the enclosed space defined by the container.

The mountings for rods 14 on the side plates 11 may comprise suitable lugs stamped integral with the side plates and turned inwardly therefrom at the respective ends of the side plates as shown in Fig. 1, and the pair of lugs for each rod 14 preferably includes an ear 20 through which the inner end 25 of the rod extends and is riveted or otherwise suitably fixed thereto as shown at 21, and a recessed support 22 in which the inner end 30 of the tube 13 and the guideway 12 mounted on the outer end of the rod is slidably received. The rods 14 for the respective superimposed trays have their lugs 20-22 positioned on side plates 11 in such vertically 35 spaced relation as to permit nesting of the trays one above another and entirely within the enclosure formed by the cover of the receptacle when the latter is closed; and to permit withdrawal of the respective trays in 40 opposite directions the lugs 20-22 for the supporting rods for the respective trays are reversed with relation to the front and rear 45 of the container as shown in Figs. 2 and 3, so that the tubes 13 for the respective trays are adapted to slide in opposite directions on 50 their rods 14 and thereby extend the trays in opposite directions beyond the front and rear 55 of receptacle 1 as shown in Fig. 1.

The construction as thus described provides for convenient nesting of the trays in vertically spaced relation above the receptacle 1 so that its cover may be closed and the respective trays as well as the body of the receptacle may form containers for various articles such as tools, etc., and the invention also provides for withdrawing and adequately 60 supporting the trays in extended position when the cover for the container is opened, so that access may be simultaneously had to both the trays and to the main body of the receptacle. The mounting of rods 14 on the 65 stamped side plates 11 permits of extremely

simple and economical manufacture and assembly of the container, and the reversed disposition of the lugs 20-22 for the respective trays permits the use of interchangeable tray units while providing for their opposite 70 extension beyond the main receptacle.

I claim:

1. A container comprising a receptacle having an open top, a cover having a top and depending side walls and adapted for displaceable mounting on the receptacle so as to define an enclosed space within the cover above the open-top receptacle, and a tray fixed against vertical displacement and slidably mounted on the receptacle for retraction 75 and support in said enclosed space when the cover is in place and adapted for extension beyond the receptacle when the cover is removed.

2. A container comprising a receptacle 85 having an open top, a cover having a top and depending side walls and adapted for displaceable mounting on the receptacle so as to define an enclosed space within the cover above the open-top receptacle, and a pair of 90 trays fixed against vertical displacement and oppositely slidably mounted in vertically spaced relation on the receptacle for retraction and support in said enclosed space when the cover is in place and adapted for extension 95 in opposite directions beyond receptacle when the cover is removed.

3. A container comprising a receptacle having an open top, a cover having a top and depending side walls and adapted for displaceable mounting on the receptacle so as to define an enclosed space within the cover above the open-top receptacle, guide rods supported by and fixed against vertical displacement relative to the receptacle above the same, and a tray fixed against vertical displacement relative to the guide rods and slidably mounted thereon for retraction in said enclosed space when the cover is in place and adapted for extension beyond the receptacle 100 when the cover is removed.

4. A container comprising a receptacle having an open top, a cover having a top and depending side walls and adapted for displaceable mounting on the receptacle so as to define an enclosed space within the cover above the open-top receptacle, guide rods supported by and fixed against vertical displacement relative to the receptacle in vertically spaced relation above the same, and a pair 115 of trays fixed against vertical displacement relative to the respective vertically spaced guide rods and oppositely slidably mounted thereon for retraction in said enclosed space when the cover is in place and adapted for extension in opposite directions beyond the receptacle when the cover is removed.

5. A container comprising a receptacle having an open top, a cover having a top and depending side walls and adapted for dis- 120

placeable mounting on the receptacle so as to define an enclosed space within the cover above the open-top receptacle, horizontal guide rods supported by the receptacle above the same, supporting tubes slidable on the guide rods, and a tray slidably mounted on the supporting tubes for relative telescoping and projection of the guide rods and the supporting tubes and tray to retract the tray in said enclosed space when the cover is in place and project the tray beyond the receptacle when the cover is removed.

6. A container comprising a receptacle having an open top, a cover having a top and depending side walls and adapted for displaceable mounting on the receptacle so as to define an enclosed space within the cover above the open-top receptacle, horizontal guide rods supported by the receptacle above the same, supporting tubes slidable on the guide rods, a tray slidably mounted on the supporting tubes, means for limiting relative telescoping and projection of the guide rods and the supporting tubes and tray to retract the tray in said enclosed space when the cover is in place and project the tray beyond the receptacle when the cover is removed, the said limiting means maintaining an appreciable telescopic engagement of the guide rods and the supporting tubes and tray when the tray is projected in order to provide a braced support for the projected tray.

7. A container comprising a receptacle having an open top, a cover having a top and depending side walls and adapted for displaceable mounting on the receptacle so as to define an enclosed space within the cover above the open-top receptacle, horizontal guide rods supported by the receptacle above the same, supporting tubes slidable on the guide rods, a tray slidably mounted on the supporting tubes, means for limiting relative telescoping and projection of the guide rods and the supporting tubes and tray to retract the tray in said enclosed space when the cover is in place and project the tray beyond the receptacle when the cover is removed, the tray when projected having a bearing support on the supporting tubes throughout approximately one-half the length of said tubes, and the supporting tubes having a bearing support of appreciable length on the guide rods.

8. A container comprising a receptacle having an open top, a cover having a top and depending side walls and adapted for displaceable mounting on the receptacle so as to define an enclosed space within the cover above the open-top receptacle, side plates projecting upwardly from the receptacle into said enclosed space and having lugs at their respective ends, guide rods extending along the side plates and supported by the lugs, and a tray slidably mounted on the guide rods for retraction in said enclosed space when the

cover is in place and adapted for extension beyond the receptacle when the cover is removed, the lugs at one end of the side plates being adapted for fixed connection of the guide rods thereto, and the lugs at the opposite end of the side plates forming recessed supports for the guide rods and tray permitting said retraction and extension of the tray.

9. A container comprising a receptacle having an open top, a cover having a top and depending side walls and adapted for displaceable mounting on the receptacle so as to define an enclosed space within the cover above the open-top receptacle, side plates projecting upwardly from the receptacles into said enclosed space and having vertically spaced lugs at their respective ends, guide rods extending along the side plates and supported by the vertically spaced lugs, and a pair of trays oppositely slidably mounted on the vertically spaced guide rods for retraction in said enclosed space when the cover is in place and adapted for extension in opposite directions beyond the receptacle when the cover is removed, the lugs for the respective guide rods including an ear at one end of a side plate adapted for fixed connection of the guide rod thereto and a recessed support at the opposite end of the side plate for slidably supporting the tray and the guide rod, the said lugs for the guide rods for the respective trays being reversed with relation to the ends of the side plates to permit said opposite extension of the respective trays.

10. A container comprising a receptacle having an open top, a cover having a top and depending side walls and adapted for displaceable mounting on the receptacle so as to define an enclosed space within the cover above the open-top receptacle, guide rods supported by the receptacle above the same, a tray having rolled edges forming guideways adapted to receive said guide rods for slidably mounting the tray for retraction in said enclosed space when the cover is in place and adapted for extension and projection of the tray beyond the receptacle when the cover is removed.

11. A container comprising a receptacle having an open top, a cover having a top and depending side walls and adapted for displaceable mounting on the receptacle so as to define an enclosed space within the cover above the open-top receptacle, side plates projecting upwardly from the receptacle into said enclosed space and having lugs at their respective ends, guide rods extending along the side plates and supported by the lugs, and a tray slidably mounted on the guide rods for retraction in said enclosed space when the cover is in place and adapted for extension beyond the receptacle when the cover is removed.

12. A container comprising a receptacle, guide rods supported by the receptacle, a tray having rolled edges forming guideways adapted to receive said guide rods for slidably mounting the tray for retraction in the receptacle or extension and projection of the tray beyond the receptacle.

In testimony whereof he has affixed his signature to this specification.
